UNITED STATES PATENT OFFICE.

SAMUEL A. NELSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT-DETECTING MECHANISM.

Application filed December 1, 1925. Serial No. 72,584.

This invention relates to a weft detecting mechanism for an automatic weft-replenishing drop-box loom.

It has been heretofore proposed to provide a single weft detector which may be moved to cooperate with a selected drop-box and to thereafter maintain said detector in cooperative relation with the selected drop-box as the boxes are shifted vertically to bring the indicated shuttle to running position.

A mechanism of this general character is shown in the prior patent to Ryon, No. 1,205,792, issued November 21, 1916.

It is the general object of my present invention to improve the positioning mechanism shown in the above mentioned patent, and particularly to provide positively actuated devices for moving the detector in either direction to cooperate with a selected drop box.

A further object is to provide an improved mechanism for positively maintaining said weft detector in such cooperative relation with the drop-box as the latter is thereafter moved to bring the indicated shuttle to running position.

My invention further relates to certain arrangements and combinations of parts which will be hereinafter described and more particularly pointed out in the appended claims.

A preferred form of the invention is shown in the drawings in which—

Fig. 1 is a side elevation of parts of a loom embodying my improvements, with the drop-boxes shown in section;

Fig. 2 is an enlarged side elevation of parts of the mechanism for selectively positioning the weft detector and for thereafter maintaining its relation to the drop-boxes;

Figs. 3 and 4 are detail sectional plan views taken along the line 3—3 in Fig. 2, and the line 4—4 in Fig. 1 respectively;

Fig. 5 is a partial plan view of the pattern chain driving sprocket;

Fig. 6 is an end elevation thereof, and

Fig. 7 is a side elevation of a cylinder gear.

Referring to the drawings, I have shown a portion of a loom frame 10 having a lay 11 pivotally mounted thereon in the usual manner. Drop-boxes 12 are mounted for se-

lective vertical movement on the lay, said drop-boxes being supported by the usual lifter rod 13 which is connected at its lower end through a link 14 to a floating lever 15.

The lever 15 is provided with a stud 16 slidable in a fixed vertical slot 17, and is connected by links 18 and 19 to bell-crank 20 and 21. These bell-crank are connected at their upper ends by vibrator links 22 and 23 to vibrator gears 24 mounted on the usual vibrator levers 25 which may be raised or lowered to cause the vibrator gears 26 and 27 to engage the upper or lower cylinder gears 28 and 29. The vibrator levers 25 are moved vertically by pattern controlled levers 30 connected to the vibrator levers by links 31. The levers 30 are selectively raised and lowered by a pattern chain driven by sprockets fixed to a driving shaft 32. The parts thus far described are or may be of the usual commercial construction and in themselves form no part of my present invention, which relates particularly to the mechanism for positioning a weft detector 33 in cooperative relation with a selected drop-box 12 and for thereafter maintaining such relation.

The weft detector 33 is indicated diagrammatically in the drawings and may be of any usual type of construction, the particular form and operation of the weft detector also forming no part of my present invention.

The detector 33 is movably mounted on a stand 34 secured to the upper end of a support 35 which is slidable in guideways in a bracket or casing 36, firmly secured to the loom frame 10. A rack plate 37 is fixed to the support 35 as indicated in Fig. 2.

A floating double rack bar 40 is also slidable in a guideway 41 in the bracket 36, its movement being parallel to that of the support 35. A pinion 42 engages the rack plate 37 on one side, and the double rack bar 40 on the other side, and is positioned vertically by a link 43 connected at its lower end to a floating lever 44.

The lever 44 is selectively positioned vertically by pattern-controlled mechanism which is essentially a duplicate of the mechanism already described for positioning the floating lever 15, the lever 44 being controlled by an additional pair of pattern lev-

ers 28 controlled by a pattern chain on the shaft 30.

A second rack bar 45 is slidable in a guideway 46 in the bracket 36 and engages a pinion 47 pivoted at 48 to said bracket. On its opposite side the pinion 47 engages one side of the double floating rack bar 40. The rack bar 45 is connected by a link 46 to the drop-box positioning lever 15 previously described, so that the rack bar 45 moves vertically simultaneously with the lifter rod 13.

The support 35 and rack bars 40 and 45 may be retained in the bracket 36 in any convenient manner, one suitable construction being indicated in Fig. 3, in which the support 35 is slidable in a dove-tailed guideway and in which the rack bars 40 and 41 are retained in their guideways by a slotted cover plate 50. The pinion 42 is also retained in position by the cover plate 50, and is connected to its link 43 by a stud 51.

The chain for moving the pattern levers 28 which locate the weft detector is preferably mounted on sprockets 55 (Fig. 5), while the chain controlling the lever 28 for the drop-boxes is mounted on sprockets 56 (Fig. 5). The sprockets 55 and 56 turn in unison about the shaft 30 but are preferably spaced so that the teeth of the sprockets 55 are half a space in advance of the teeth of the sprocket 56, for a purpose to be described.

The operation of my improved weft detecting mechanism is as follows:—

The pattern levers 28 for the weft detector are moved by the corresponding pattern chain to position the floating lever 44 so as to bring the weft detector 33 opposite to the shuttle which is about to become active. This movement of the lever 44 raises or lowers the pinion 42, thus rotating the pinion on the temporarily fixed rack 40 and causing a raising or lowering of the rack plate 37 and of the associated weft detector support 35. The weft detector is thus located opposite to the desired shuttle box.

The pattern levers 28 for the drop-boxes are then actuated, causing the cylinder gears to position the floating lever 15 so as to bring the desired shuttle to running position. As the lifter rod 13 is thus raised or lowered, the rack bar 45, which is also connected to the lever 15, will be raised or lowered a corresponding distance, causing rotation of the pinion 47 about its fixed pivot 48. This rotation of the pinion 47 in turn causes a vertical movement of the floating double rack bar 40 in the reverse direction and corresponding movement of the rack plate 37 in the same direction as the movement of the rack bar 45.

The pinions 42 and 47 are of the same size and pitch and consequently the rack plate 37 is moved in the same direction as the rack bar 45 at the same time and to the same extent, thus maintaining the detector

33 in operative relation with the shuttle in the selected shuttle box.

Both the pinion 42 and the rack bar 45 are moved vertically by direct and positive connections from the vibrator gears 24 which are rotated by the positively driven cylinder gears 26 and 27. Ample power is thus provided for moving all parts of the actuating mechanism for the weft detector and drop boxes.

The cylinder gears 26 and 27 are preferably made in two longitudinally disposed sections, as indicated in Fig. 7, one section being spaced a part of a revolution in advance of the other so that the detector 33 may be moved opposite to its selected shuttle box before the boxes themselves begin to move.

Having thus described my invention, it will be seen that I have provided a very simple and positive mechanism for definitely locating the weft detector in alignment with a selected shuttle box, and for thereafter maintaining such alignment during the movement of said shuttle box to running position.

Having attained this result, I do not wish to be limited to the details herein disclosed otherwise than as set forth in the claims, but what I claim is:

1. In a weft replenishing drop-box loom, a weft detector, pattern controlled means to move said weft detector into alignment with a selected shuttle box, and means for thereafter maintaining cooperative relation of said detector and shuttle box during movement of the selected shuttle box to running position, said pattern controlled means being positively actuated in both directions and being effective to give said detector positive positioning movements in both upward and downward directions.

2. In a weft replenishing drop-box loom, a weft detector, pattern controlled means to move said weft detector into alignment with a selected shuttle box, and means for thereafter maintaining cooperative relation of said detector and shuttle box during movement of the selected shuttle box to running position, said pattern controlled means comprising positively actuated members, and positive gear connections therefrom to said weft detector, whereby said detector is moved positively in both upward and downward directions.

3. In a weft replenishing drop-box loom, a weft detector, pattern controlled means to move said weft detector into alignment with a selected shuttle box, and means for thereafter maintaining cooperative relation of said detector and shuttle box during movement of the selected shuttle box to running position, said latter means including a positive gear connection by which said detector is moved positively in both upward

and downward directions and through which said cooperative relation is maintained.

4. In a weft replenishing drop-box loom, a weft detector, pattern controlled means to move said weft detector into alignment with a selected shuttle box, and means for thereafter maintaining cooperative relation of said detector and shuttle box during movement of the selected shuttle box to running position, said pattern controlled means including cylinder gears, vibrator gears selectively associated therewith, and positive mechanical connections between said vibrator gears and said weft detector for moving the latter to selected definite positions and effective to move said detector positively in both upward and downward directions.
5. In a weft replenishing drop-box loom, a weft detector, a detector stand, a vertically movable support for said stand, a fixed guideway for said support, a rack on said support, a floating rack bar slideable parallel to said support, a second rack bar slideable parallel to said support, a pinion mounted on a fixed pivot and engaging said second rack bar and said floating rack bar, and a second pinion engaging said floating rack bar and the rack on said support, said second pinion and said second rack bar being connected respectively to pattern controlled devices by which they may be selectively positioned vertically.

6. A weft detector positioning mechanism as set forth in claim 5, in which the two pinions are of equal diameter and pitch, and in which said second rack bar gives said support simultaneous vertical movements in the same direction as the movements of said rack bar.

7. In a weft replenishing drop-box loom, a weft detector, and means for selectively positioning said detector, said means including separate pattern chains for positioning the detector and the drop-boxes, and means for rendering said chains alternately operative.

8. In a weft replenishing drop-box loom, a weft detector, and means for selectively positioning said detector, said means including separate pattern chains for positioning the detector and the drop-boxes, means for rendering said chains alternately operative, vibrator gears connected to actuate said weft detector support and said drop-boxes, and cylinder gears for moving said vibrator gears, said cylinder gears being formed in two axially disposed parts, and the toothed portion of one part being advanced angularly relative to the toothed portion of the other, whereby the detector is selectively positioned before movement of the drop boxes.

In testimony whereof I have hereunto affixed my signature.

SAMUEL A. NELSON.
